Japanese Office Action, dated Nov. 12, 2015, for Japanese Application No. 2015-009330, with a partial English translation.

Primary Examiner — Eliza Z Bennett-Hattan

(74) *Attorney, Agent, or Firm* — Birch, Stewart, Kolasch & Birch, LLP

(57) **CLAIM**

The ornamental design for an endoscope, as shown and described.

DESCRIPTION

FIG. 1 is a perspective view showing our new design; FIG. 2 is an enlarged partial perspective view thereof; FIG. 3 is a front view of an endoscope thereof; FIG. 4 is a rear view thereof; FIG. 5 is a plan view thereof; FIG. 6 is a bottom view thereof; FIG. 7 is a right side view thereof; FIG. 8 is a left side view thereof; FIG. 9 is an enlarged partial left side view of line 10-10 section of FIG. 3; FIG. 10 is an enlarged partial view taken along line 10-10 section of FIG. 3; FIG. 11 is an enlarged partial view taken along line 11-11 of FIG. 4; FIG. 12 is an enlarged partial view taken along line 12-12 of FIG. 5; FIG. 13 is an enlarged partial view taken along line 13-13 of FIG. 6; FIG. 14 is a view from line 14-14 of FIG. 10; and, FIG. 15 is a sectional view which omits internal mechanism and is taken along line 15-15 of FIG. 14.

The details outlined in dashed broken lines depict unclaimed portions of the endoscope and form no part of the claim. The appearance of any portion of the article between the intermediate omitted portion forms no part of the claimed design.

1 Claim, 10 Drawing Sheets
